SAFETY GUARD SCREEN

Charles P. Majkrzak, South Orange, N. J., assignor to Orange Screen Company, Maplewood, N. J., a corporation of New Jersey

Application January 23, 1946, Serial No. 642,973

9 Claims. (Cl. 160—378)

1

This invention relates to safety screen guards for use more particularly in asylums, hospitals and the like.

Safety guards comprising bars have a bad psychological effect on inmates of insane asylums or the like, and in order to avoid this effect it has been proposed to replace the bars with a screen to which the patients are already accustomed. Such a screen, which should be of sufficiently fine mesh to exclude flies and other insects, must be strong enough to absorb the impacts of bending or pushing to which the patient may resort and should be so supported in its frame as to minimize the danger of cutting the screen. Also, it is necessary to support the screen wire with resilient shock-absorbing springs in order to cushion the screen against violent impacts and to decelerate in a relatively short distance the motion of heavy bodies thrown against the screen.

It has been suggested that coil springs can be used as shock absorbers for supporting the screen wire, but the use of such springs renders a safety screen very complex and bulky. A very large number of heavy and relatively large diameter coil springs are required to provide the necessary shock-absorbing properties. Moreover, inasmuch as such springs are formed of wire of relatively smaller diameter than the coil, it is necessary to reinforce the edge of the screen or provide relatively complex clamping elements on the ends of the springs to prevent the springs from tearing out of the screen under impact.

An object of the present invention is to provide a simplified form of shock-absorbing spring for safety guard screens that is readily attached to the edge of the screen wire.

Another object of the invention is to provide an improved type of shock-absorbing spring for safety guard screens that is readily assembled with the frame of the screen.

A further object of the invention is to provide a safety guard screen having a relatively small number of shock-absorbing springs that are capable of absorbing heavy impacts without danger of tearing away from the screen wire.

A still further object of the invention is to provide a safety guard screen in which the screen wire may be deflected a sufficient distance to decelerate the impact of heavy bodies without coming into contact with the frame of the screen and being cut or torn thereby.

Other objects and advantages of the invention will become apparent from the following description of a typical form of safety guard screen embodying the present invention.

2

In accordance with this invention, a typical safety guard screen may include a channel-like frame adapted to be mounted in the sash frame aperture of a building, and having a screen wire panel resiliently mounted with its edges in the channels of the frame in such a manner as to absorb heavy impacts and to prevent removal of the screen panel. More particularly, the panel is retained by means of relatively wide springs formed of flat spring metal having semi-cylindrical or scroll-like spring portions and free ends that are clamped or otherwise secured to the screen panel. The spring members are mounted within the frame with their panel-engaging ends extending inwardly for movement in the plane of the panel or transversely with respect to the frame so that they can be deflected under impact while resiliently absorbing the impact.

Spring shock absorbers of the type described above can be secured firmly to the edges of the screen wire panel without substantial reinforcement of the edge of the panel, and because of their strength and width, relatively few of the spring shock absorbers are required.

Moreover, by providing the frame with internal grooves substantially complementary to the semi-cylindrical or scroll-like portion of the spring shock absorbers, the entire safety guard screen can be assembled easily and the shock absorbers anchored firmly against accidental displacement or removal from the indoor side of the screen.

For a better understanding of the invention, reference may be had to the accompanying drawings, in which:

Figure 1 is a vertical section through the screen guard frame on the line 1—1 of Figure 2;

Figure 2 is a transverse section on the line 2—2 of Figure 1 showing the screen in normal position;

Figure 3 is a corresponding section on the same line, as indicated at 3—3, showing the screen under maximum load;

Figure 4 is a cross section through a side member of the screen frame on the line 4—4 of Figure 1; and

Figure 5 is a cross section through a side member of the screen frame on the line 5—5 of Figure 1.

The invention will be described with reference to a preferred embodiment illustrated in the drawings for purposes of disclosure.

The screen guard comprises a frame F, a screen panel S and spring shock-absorbing units A for supporting the panel S in the frame.

The shock absorbers A are preferably con-

structed of suitable spring material in plate or strip form of required thickness, so that they yieldingly resist the load due to the maximum impacts to which the screen may be subjected. All of the shock absorbers are preferably of the same construction and dimensions and may be secured directly to the edges of the screen.

Each shock absorber A consists of a straight or flat body portion 6 terminating at one end in a reversely bent portion providing an attaching 10 clamping flange 8 spaced from the body portion 6 to provide a channel for receiving an edge of the screen panel. The screen panel is cut to the proper dimensions, so that it will be under a suitable tension when the shock absorbers are connected to the frame.

In assembling the shock absorbers with the screen panel the flanges 8 of the shock absorbers are preferably passed under and accurately spaced along the edges of the panel with the body 20 portion 6 resting on top of the panel, and then the flanges 8 are hammered or pressed toward the body portions of the shock absorbers to clamp the edges of the screen between the flanges and the body portions of the shock absorbers. If 25 desired, the edges of the screen panel may be doubled over or otherwise reinforced to strengthen the edges of the panel although in most cases this is unnecessary. The flanges may be spot welded to the body portions of the panel S or they may be held in clamping position by any suitable means. After the shock absorbers have been secured to the screen, they are swung through an angle of 180° about the free ends of the flanges 8 into the position shown in the drawings.

The shock absorber A is provided at its other end with a semi-cylindrical portion or scroll 10 having a free end that is spaced from the body 6 a suitable distance to permit the body 6 to move angularly with the edge of the screen panel S as 40 the panel is moved angularly by impacts on the face of the panel.

The free end of the scroll 10 is bent outwardly to provide a flange 12 which is preferably inclined slightly to the rear of the radius through 45 the free end of the scroll. The flange 12 holds the scroll 10 from rotating under impacts on the face of the screen. The object and function of this construction will appear more clearly after the frame has been described.

The frame F which is generally of inwardly opening channel shape comprises a main frame member 16 which may be made from an extruded part which is cut into lengths to provide the side and top and bottom members of the frame.

The main frame member 16 may comprise a generally tubular rectangular body 18 adapted to be mounted and fitted in the frame of a window opening. The inner side of the body 18, that is, with respect to the completed frame, is provided with a groove 20 (Figures 4 and 5) to receive an auxiliary indoor frame member 22, which will be described in detail later.

The inner side of the body 18 with respect to the frame is provided near its outdoor edge with a flange 24 having a portion of its outside face lying in the plane of the outdoor face of the body 18. The flange 24 is provided with a semi-cylindrical groove 26 in its inner face to receive the scrolls 10 of the shock absorbers A.

The inner face of the flange 24 at the edge of the groove 26 is provided with a groove 28 forming a seat for the flange 12, and a shoulder 30 for engaging the end of the flange 12. The end of the flange 24 is tapered outwardly to permit

full angular movement of the inner or screen ends of the shock absorbers A under maximum load due to impacts on the face of the screen.

The outer face of the flange 24 may be tapered inwardly as indicated at 34 for the sake of appearance, to save material and to facilitate the formation of the holes 36 for receiving the inclined securing screws 38 employed in securing the indoor frame member 22 to the main frame member 16. The free edge 39 of the flange 24 may be rounded to prevent cutting of the screen under loads which are greater than the maximum load for which the shock absorbers are constructed.

The indoor frame member 22 is provided with a retaining flange 40 adapted to engage in the groove 28 in the main frame member 16. The outer or indoor face of the frame member 22 may be flat and extends inwardly substantially the same distance as the flange 24.

The inner face of the frame member 22 is preferably provided with a recess 42 at its inner edge to receive the edge of the screen and the inner ends of the shock absorbers A when the latter are under normal load.

Projecting from the inner face of the frame member 22 is a rib or flange 44 which extends in a direction normal to the inclined face 34 of the flange 24 of the main frame member 16 and which is provided with an end conforming to the groove 28 and the shoulder 30 on the flange 24 of the main frame member 16. The frame member 22 may be cut from a strip of extruded material having a continuous rib 44 that is cut away to provide the projections 46 defining the spaces 48 to receive the body portions 6 of the shock absorbers A. The projections 46 are tapped and threaded as indicated to receive the fastening screws 38 by means of which the indoor frame member 22 is secured to the main frame member 16.

As disclosed in Figure 1, the shock absorbers A are preferably equidistantly spaced along the edges of the screen panel S so as to properly cushion the screen along its side, top and bottom edges. These shock absorbers are slightly narrower than the openings, so that the panel will be properly positioned in the frame when the shock absorbers are connected to the main frame member. The face of the screen panel and the dimensions of the shock absorbers are so proportioned that the screen will be placed under a suitable normal tension when the panel is connected to the frame.

As disclosed in Figure 3, when the shock absorbers A and the center of the screen panel S are under a maximum load, the screen ends of the shock absorbers are in alignment with the planes of the edges of the panel, so that there is no cutting action between the shock absorbers and the panel as the edges of the panel are deflected angularly. This view is taken horizontally through the middle portion of the panel S and shows the maximum movement of this portion of the panel. The amount of movement of the side edges of the panel at points above and below this plane gradually decreases toward the top and bottom of the frame, and the amount of deflection of the panel edges at the top and bottom of the frame are proportionately less than at the middle section of the screen depending upon the relation of the length of the screen to the width of the screen.

It is to be noted that by making the shock absorbers relatively wide it usually will be unnecessary to reinforce the edges of the screen

that are embraced by the clamping portions of the shock absorbers.

As shown in Figures 1 and 5, the inner or indoor frame member 22 prevents access to the clamping means and also to the interior of the frame 16 to unseat the shock absorbers. The frame member 22 can be removed from the main frame member 18 only by first removing the connecting screws which are accessible only from the exterior of the building.

While the invention has been described with reference to a preferred embodiment illustrated, it is to be understood that the right is reserved to all such changes and modifications as fall within the principle of this invention and the scope of the appended claims.

I claim:

1. In a safety guard, a frame for a guard member comprising indoor and outdoor members secured together and providing a space between their inner edges to accommodate angular deflections of said guard member, said guard member having its edges located within said space, and shock absorbers, each attached at one end to an edge of said guard member within said space and secured at its other end within said frame, each of said shock absorbers terminating at said other end in a scroll, said frame being provided with seats for said scrolls.

2. In a safety guard, a frame for a guard member comprising indoor and outdoor members secured together and providing a space between their inner edges to accommodate angular deflections of said guard member, said guard member having its edges located within said space, shock absorbers, each attached at one end to an edge of said guard member within said space and secured at its other end within said frame, each of said shock absorbers being provided at said other end with a scroll and an outwardly extending flange on the end of said scroll, and said frame being provided with seats for said scrolls and said flanges.

3. In a safety guard, a frame for a guard member comprising indoor and outdoor members secured together and providing a space between their inner edges to accommodate angular deflections of said guard member, said guard member having its edges located within said space, shock absorbers, each attached at one end to an edge of said guard member within said space and secured at its other end within said frame, each of said shock absorbers being provided at said other end with a scroll, an outwardly extending flange on the end of said scroll, said frame being provided with seats for said scrolls and flanges, and said first-mentioned end of said shock absorber being provided with a return bent portion constituting a clamping flange for clamping the shock absorber to the edge of said screen.

4. In a safety guard, a frame for a guard member comprising indoor and outdoor members secured together and providing a space between their inner edges to accommodate angular deflections of said guard member, said guard member having its edges located within said space,

shock absorbers, each attached at one end to an edge of said guard member within said space and secured at its other end within said frame, each of said shock absorbers being provided at said other end with a scroll, an outwardly extending flange on the end of said scroll, said frame being provided with seats for said scrolls and said flanges, and said first-mentioned end of said shock absorber being provided with a return bent portion constituting a clamping flange for clamping the shock absorber to the edge of said screen, said scroll and clamping flange being located on opposite sides of said guard member.

5. A shock absorber for connecting a guard member to a frame, comprising a body having a scroll at one of its ends and a clamping flange for attaching a guard member thereto at its other end.

6. A shock absorber for connecting a guard member to a frame, comprising a body having a scroll of less than 360° at one of its ends, an outwardly extending flange on the free end of said scroll and a clamping flange on the other end of said body for attaching a guard member thereto.

7. A shock absorber for connecting a guard member to a frame comprising a body having a scroll at one of its ends and a clamping flange for attaching a guard member thereto at its other end, said scroll and clamping flange being located on opposite sides of said body.

8. In a safety guard screen, the combination of a frame having inwardly opening channel-like sides and ends, a plurality of wide shock-absorbing springs having nearly cylindrical spring portions mounted in said ends and sides of said frame and inwardly projecting free ends substantially tangential to said cylindrical portions, a screen panel, and means for securing the edges of said panel to the free ends of said shock-absorbing springs.

9. In a safety guard screen, the combination of a screen panel, a plurality of spring shock absorbers adapted to be secured to the edge of said panel, each shock absorber comprising a nearly cylindrical spring portion having a wide free end projecting substantially tangentially from said nearly cylindrical portion, means for securing said free end to said panel in substantially parallel relationship to said panel, and a frame member having recesses for receiving and retaining said nearly cylindrical portions of said shock absorbers.

CHARLES P. MAJKRZAK.
